ATTORNEY.

UNITED STATES PATENT OFFICE.

ARTHUR E. SMITH, OF LOS ANGELES, CALIFORNIA.

SYRINGE.

Application filed October 26, 1927. Serial No. 228,916.

This invention relates to improvements in hypodermic syringes.

The general object of this invention is to provide an improved syringe wherein the substance to be ejected is contained in a cartridge-like ampule which is provided with a slideable stopper and wherein means is provided for automatically correctly positioning an ampule in the syringe when the operating member of 10 the syringe is arranged in an operative position, and wherein in the process of injecting, the various parts of the syringe coact to move the stopper relative to the ampule to force out the contents of the ampule.

Another object of this invention is to provide a syringe having an ejecting plunger which is adapted to enter a constricted portion of an ampule contained therein with means for automatically and correctly positioning the ampule before the plunger enters the constricted portion of the ampule.

An additional object of my invention is to provide a novel means for centering an ampule in a syringe.

Other objects of the invention will be apparent from the following description taken in connection with the accompanying drawings wherein:

Fig. 1 is a central longitudinal section 30 through my improved syringe showing an ampule therein and showing the ejecting plunger about to enter the ampule.

Fig. 2 is a view similar to Fig. 1 showing the positions of the various elements after the 35 contents of the ampule has been ejected.

Fig. 3 is a transverse section of the syringe taken on line 3—3 of Fig. 1.

Fig. 4 is a fragmentary longitudinal section of the syringe operating member showing a modified form of ampule positioning means.

Fig. 5 is a transverse section taken on line 5—5 of Fig. 4.

Fig. 6 is a view similar to Fig. 4 showing another modified form of ampule positioning means.

Fig. 7 is a view similar to Fig. 4 showing still another modified form of ampule positioning means and

Fig. 8 is a section taken on line 8—8 of Fig. 7.

Referring to the drawings by reference characters I have indicated a hypodermic syringe embodying the features of my invention generally at 10. This syringe comprises a hollow body portion or barrel 11 having

screw threads 12 provided at one end and having its other end beveled as at 13. Adjacent one end of the barrel 11 a cross bar 14 is provided and in the barrel 11 equally spaced 60 elongated slots 15 are provided.

The end of the syringe opposite the cross bar 14 is provided with a tip 16 which is in threaded engagement with the threads 12 of the barrel. This tip 16 has a reduced end 17 and is provided with a tapered recess 18 which 65 communicates with an aperture 19 which extends through the reduced end 17. A hypodermic needle 20 is adapted to be positioned on the reduced end 17 of the tip 16 and the 70 end 17 may be either threaded or tapered as shown.

An operating member indicated generally at 22 is adapted to be slidably mounted within the barrel 11. This operating member includes a barrel 23 having an elongated aperture 24 provided in one side thereof and an end member 25 which includes a thumb piece 26. An ejecting plunger 27 is detachably secured to the end member 25 and includes an 80 enlarged head 28 and a reduced tip 29.

Surrounding the plunger 27 and within the barrel 23 I provide an ampule positioning member 30. This positioning member 30 is provided with a conical recess 32 and a central stem 33 which surrounds the plunger 27 and may be slightly spaced therefrom. A plurality of spring fingers 34 are provided in the peripheral wall of the positioning member and are adapted to frictionally engage the 85 inner wall of the barrel 23 of the operating member.

One type of ampule such as may be used in connection with my improved syringe is indicated generally at 36. This ampule as 95 shown is preferably made of glass and comprises a tubular body 37 having a constricted end 38 which is normally closed but is made open when the ampule is made ready for use by breaking away a portion of the ampule. 100 The opposite end of the ampule is also constricted as at 39 and like the end 38 is normally closed but is made open by breaking away a portion of the ampule before it is inserted in the syringe. This constricted end 39 is provided with a resilient collar 40 which is preferably made of a good grade of rubber.

A stopper 41 is normally positioned in the ampule adjacent the constricted end 38 and is movable within the ampule to act as a piston 110 to expel the contents of the ampule out through the constricted end 39. The stopper

41 is preferably made of a good grade of rubber and is provided with a metal washer 42 having a central aperture therethrough of approximately the same size as the diameter 5 of the plunger tip 29. The stopper 41 is also shown as provided with an aperture 44 of approximately the same size as the size of the aperture in the washer.

In using my improved syringe 10 the operating member 22 is removed from the syringe barrel 11 and the positioning member 30 moved to the open end of the operating member to the position shown in Fig. 1. An ampule 36, having been previously made ready for use, is then inserted into the barrel 11 so that the resilient collar 40 is positioned in the tapered recess 18 of the tip 16 as shown. The operating member 22 is then replaced in the syringe barrel 11 and moved towards the tip 16.

As the operating member is moved the positioning member moves with it due to engagement of the spring fingers 34 until it engages the ampule as shown in Fig. 1. As the positioning member 30 engages the ampule it correctly centers the ampule relative to the ejecting plunger 27 so that upon further movement of the operating member the plunger head 28 will pass through the opening 38 in the constricted end 39 and the reduced tip 29 will be positioned in the aperture of the washer 42 when the head 28 abuts the washer.

Upon a further movement of the operating member towards the tip 16 the ejecting plunger 27 will cause the stopper 41 to move and act as a piston to expel the contents of the ampule out through the constricted end 39 and into the hypodermic needle 20.

All during the ejecting movement of the operating member 22 the frictional engagement of the positioning member 30 therewith will cause a resilient pressure to be exerted upon the ampule. Even should the ejecting movement of the operating member cease for a while the positioning member would exert a slight pressure upon the ampule and thus retain a fluid tight seal between the collar 40 and the tapered recess 18 of the syringe tip 16. The pressure exerted upon the ampule by the positioning member is only removed when the operating member is moved away from the tip 16.

After the contents of the ampule have been ejected as shown in Fig. 2 the operating member 22 and the ampule are removed from the syringe, the positioning member 30 moved to the open end of the operating member, and the syringe is then ready for use again.

In Figs. 4 and 5 I have shown the operating member 22 provided with a modified form of positioning member indicated generally at 45. This positioning member includes a conical recess 46 and an externally screw threaded stem 47 which surrounds the ejecting plunger 27 and is spaced therefrom. The

peripheral wall of this positioning member is provided with a plurality of slits as shown at 48 and is adapted to be internally engaged by a coiled spring 49. A cap 50 provided with internal screw threads to match the threads 70 on the stem 47 is adapted to move within the positioning member to compress the spring to cause the spring to expand in diameter and thus expand the peripheral wall of the positioning member to frictionally engage the inner wall of the barrel 23 of the operating member.

In Fig. 6 I have shown the operating member 22 provided with another modified form of positioning member indicated generally at 55. This positioning member includes a conically recessed portion 56 and an externally screw threaded stem 57 which surrounds the ejecting plunger 27 and is spaced therefrom. The peripheral wall of this positioning member is preferably internally tapered from the bottom to the top outward and is provided with a plurality of slits 58.

A plug 59 having a hub 60 thereon provided with internal screw threads to match the threads on the stem 57, is adapted to move within the peripheral wall of the positioning member. The outer face of the peripheral wall of the plug 59 is preferably tapered to correspond to the taper of the inner face of 95 peripheral wall of the positioning member. When the plug 59 is moved toward the recessed end of the positioning member the taper on the plug causes the peripheral wall of the positioning member to expand and 100 frictionally engage the inner face of the barrel 23 of the operating member 22.

In Fig. 7 I have shown the operating member 22 provided with another modified form of positioning member indicated at 65. This 105 positioning member includes a conical recess 66 and a stem 67 which surrounds the ejecting plunger 27 and is spaced therefrom. The outer perimeter of the peripheral wall 68 of this positioning member is slightly less than 110 the internal perimeter of the operating member barrel but it is flattened out of a true cylindrical shape as clearly shown in Fig. 8. The wall 68 is resilient so that frictional engagement between the barrel 23 of the operating member and the positioning member is obtained.

From the foregoing description it will be apparent that I have provided an improved syringe having novel ampule positioning means provided therein and one which is of simple construction and highly efficient in use.

Having thus described my invention, I claim:

1. In a syringe adapted to receive an ampule, a barrel, a tubular operating member adapted to move longitudinally in said barrel, a plunger associated with said operating member and movable therewith, an ampule

positioning member in said operating member and surrounding said plunger, said positioning member being movable relative to said operating member and having frictional engagement with said operating member.

2. In a syringe adapted to receive an ampule, a barrel, a tubular operating member adapted to move longitudinally in said barrel, a plunger associated with said operating member and movable therewith, an ampule positioning member in said operating member and surrounding said plunger, said positioning member being normally movable with said operating member and being adapted to 10 be moved relative to said operating member and having frictional engagement with said operating member.

3. The combination of a syringe including a barrel, said barrel including a hollow body portion adapted to receive an ampule, an ampule positioning member movable in said barrel, a plunger adapted to enter an ampule in said barrel, said positioning member being adapted to engage the end portion of the 25 ampule and correctly hold the ampule in position and means including a part integral with said positioning member for holding said positioning member in rigid engagement with an ampule in said barrel.

4. The combination of a syringe including a barrel, a tubular operating member adapted to move longitudinally in said barrel, a plunger, an ampule adapted to fit in said barrel and said operating member, said ampule including a hollow body portion, a stopper in said body portion and an ampule positioning member movable in said barrel to center an ampule therein.

5. The combination of a syringe including a barrel, an ampule in said barrel, said ampule including a hollow body portion, a stopper in said body portion, an operating member in said barrel, means movable along said operating member for centering an ampule and means to hold said movable means in engagement with an ampule.

6. The combination of a syringe including a barrel, a closure for one end of said barrel, an ampule adapted to fit in said barrel, said ampule including a hollow body portion, a stopper in said body portion, a plunger associated with said closure, an ampule positioning member associated with said closure, said plunger being adapted to enter said ampule and engage said stopper and means integral with said ampule positioning member coacting with said closure for holding said member in position to correctly position said ampule.

7. The combination of a syringe including a barrel, a tubular operating member adapted to move longitudinally in said barrel and including a plunger, an ampule adapted to fit in said barrel and said operating member, said ampule including a hollow body portion, a stopper in said body portion, an ampule

positioning member in said operating member, said plunger being adapted to enter said ampule and engage said stopper upon movement of said operating member, said positioning member being adapted to engage said 70 ampule and correctly position said ampule, said positioning member being in frictional engagement with said operating member and being normally movable with said operating member, and said operating member being 75 movable relative to said positioning member when said positioning member engages an ampule in said barrel.

8. The combination of a syringe including a barrel, a recess in one end of said barrel, a closure for the other end of said barrel, an ampule adapted to fit in said barrel, said ampule including a hollow body portion, a stopper in said body portion, a resilient collar on said body portion, said resilient collar being 85 adapted to fit within said recess in said barrel to form a fluid tight seal between said ampule and said barrel, a plunger associated with said closure, an ampule positioning member associated with said closure, said plunger being adapted to enter said ampule and engage said stopper, said ampule positioning member being adapted to engage and correctly position said ampule before said plunger 90 engages said stopper, said positioning member being movable relative to said closure and said plunger, and said positioning member having frictional engagement with said closure.

9. The combination of a syringe including a barrel, a recess in the end of said barrel, a tubular operating member adapted to move longitudinally in said barrel and including a plunger, an ampule adapted to fit in said barrel and said operating member, said ampule 105 including a hollow body portion, a stopper in said body portion, a resilient collar on said body portion, said resilient collar being adapted to fit within said recess in said barrel to form a fluid tight seal between said ampule and said barrel, an ampule positioning member in said operating member, said plunger being adapted to enter said ampule and engage said stopper upon movement of said operating member, said positioning member being adapted to engage said ampule and correctly position said ampule before said plunger enters said ampule, said positioning member being in frictional engagement with said operating member and being normally 110 movable with said operating member, and said operating member being movable relative to said positioning member when said positioning member engages an ampule in said barrel.

10. In a syringe adapted to receive an ampule, a barrel, a tubular operating member adapted to move longitudinally in said barrel, a plunger associated with said operating member and movable therewith, an ampule 130

positioning member disposed within said operating member, said positioning member being made of a resilient metal and including annular peripheral side walls and a conically shaped bottom wall, said conical bottom wall merging into a stem surrounding said plunger and the inner side walls of said stem being spaced from said plunger, said peripheral side walls being split for part of their length to form a plurality of spring fingers, said fingers being free on three sides thereof from said side walls and being formed to exert outward pressure against the inner wall of said operating member.

15. 11. In a syringe adapted to receive an ampule, a barrel, a tubular operating member adapted to move longitudinally in said barrel, a plunger associated with said operating member and movable therewith, an ampule 20 positioning member disposed within said operating member, said positioning member being made of resilient metal and including an-

nular peripheral side walls and a conically shaped bottom wall, said conical bottom wall merging into a stem adapted to surround said plunger and the inner side walls of said stem being spaced from said plunger, the inner face of said peripheral side walls being tapered outwardly from the bottom up and being split the major portion of their length to provide a plurality of resilient sections, said stem being externally threaded, an expanding member movable within said positioning member side walls, said expanding member including a hub threaded to engage the threads of said stem and said expanding member when moved towards said bottom being adapted to expand said peripheral wall of said positioning member to cause said wall to frictionally engage the inner face of said operating member.

In testimony whereof, I hereunto affix my signature.

ARTHUR E. SMITH.
